(57) **CLAIM**

We claim the ornamental design for a tool for sighting in a firearm sight such as a red dot sight or laser or the like, as shown and described.

DESCRIPTION

FIG. 1 is a perspective view of a tool for sighting in a firearm sight such as a red dot sight or laser or the like;

FIG. 2 is a perspective view thereof;

FIG. 3 is a side view thereof;

FIG. 4 is a side view thereof;

FIG. 5 is a top view thereof;

FIG. 6 is a bottom view thereof;

FIG. 7 is a front view thereof; and,

FIG. 8 is a rear view thereof.

The broken lines showing portions of the article are included for the purpose of illustration only and do not form part of the claimed design.

1 Claim, 5 Drawing Sheets
